& Carpenter, Atty's

UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

NOZZLE.

Application filed March 10, 1920. Serial No. 384,821.

This invention relates in general to pouring nozzles for cans and containers of various kinds, and has more particular reference to nozzles provided for use on cans 5 adapted to contain liquids, as oils and the like.

A principal object of this invention is the provision of a nozzle and cap closure therefore, both so constructed that the nozzle may 10 be sealed against liquid leakage by merely positioning the closure and turning it to a locked position, and without requiring particular care in the operation or the application of unusual force.

15 The invention contemplates the provision of a nozzle having yielding packing for bearing against the end of the nozzle, together with means for holding the nozzle end against such packing with sufficient tightness; and contemplates also the provision 20 of a face over which said nozzle end is moved slightly in the closing operation and in such movement forming the face into a co-operating closing surface with said nozzle.

25 Another object of the invention is the provision of a nozzle so constructed that upon desired occasion the contents may be readily poured therefrom in minute quantities, as for example, a drop at a time.

30 Another object of the invention is the provision of a nozzle having these and other advantages, which will be cheap to construct, which will be of easy manipulation without particular instructions, and which will be compact and of pleasing appearance.

35 Numerous other objects and advantages will be apparent as it is better understood from the following description, which taken in connection with the accompanying drawing discloses a preferred embodiment thereof.

On the drawing,—

40 Figure 1 is a perspective view of a can provided with a nozzle embodying my invention;

Fig. 2 is a bottom plan view of the cap for said nozzle;

Fig. 3 is a section taken transversely of the nozzle and showing certain details of 50 construction;

Fig. 4 is a section taken axially of the nozzle and showing the cap in place; and

Fig. 5 is an enlarged side elevation of the nozzle, parts being removed or broken away

to disclose the relative positions of certain internal parts.

For the purpose of illustrating my invention I have shown on the drawing a can 11 of any usual or preferred construction and from which a nozzle 12 extends up. This 60 nozzle comprises a cylindrical body, preferably of sheet metal, having an inwardly extending bead or annular depression 13 near its top terminating in an edge 14 extending out beyond an upper rounded part 65 15. Just below the bead or depression 13 the material of the nozzle is pressed outwardly at 16 to form hollow projecting shoulders 17 arranged at intervals about the circumference of the nozzle. A cap, indicated at 70 18, is provided with an outer cylindrical flange 19 adapted to extend down about the upper end of the nozzle and at the bottom the flange 19 is provided with inwardly extending flange parts 21 in number and arrangement corresponding to the number and arrangement of the shoulders 17. A disk of cardboard or other material of appropriate yielding qualities 22 is positioned within the cap and upon this is provided a thinner 75 paraffine cover disk 23. The dimensioning of the parts is preferably such as to permit the flange parts 21 to come into close registration with the underside of the shoulders 17 when the cap is pushed down tightly 80 against the top of the nozzle. The outer surface of the cap is serrated or knurled to permit the imparting to it of a partial turn to bring the flange parts 21 under the shoulders to lock the cap in place. Each 85 flange part 21 is provided with a depression 24 at one end to limit this turning movement when the shoulders are completely engaged with the flange parts 21. In this closing 90 action the relatively thicker and more yielding cardboard disk 22 is compressed and the nozzle end slides easily over the paraffine and forms an accurate seat.

95 Construction of the nozzle end is of peculiarly desirable form since it facilitates the 100 pouring out of the can contents in accurately controllable small amounts. That is to say, the curved or beaded part 13 acts as a dam to hold back the contents when it is desired to pour material out a drop at a time as is not infrequently necessary in the pouring 105 of olive oil for salad purposes. That is to say, the can may be tilted until pouring is

about ready to commence and the body of the material is held back until it slightly overflows.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

- 15 1. A sheet metal nozzle for containers formed at its mouth with an inward peripheral bend to obstruct the flow of liquid which is desired to be delivered by drops, said inward bend terminating in an outwardly turned marginal lip which, together with the concave outside contour of the nozzle at said bend, prevents the fluid from running down on the outside of the nozzle, said nozzle being formed with outwardly 20 pressed and projecting horizontal hollow shoulders, a gasket resting on said lip of the nozzle, and a sheet metal cap bearing on said gasket and having a peripheral flange depending below said shoulders, the lower part of said depending flange being bent inwardly at intervals to form flanges to engage under said shoulders of the nozzle, the said flanges being formed with upwardly bent parts in line with said shoulders to be arrested by said shoulders when the cover is turned into sealing position.
- 25 2. A sheet metal nozzle for containers formed at its mouth with an inward peripheral bend to obstruct the flow of liquid which is desired to be delivered by drops, said inward bend terminating in an upwardly and outwardly turned marginal lip which, together with the concave outside 30 contour of the nozzle at said bend, prevents the fluid from running down on the outside of the nozzle and drains any residue back into the container, a gasket resting on the top of said lip of the nozzle, and a sheet metal cap bearing on said gasket, said nozzle and cap having detachable interlocking means to hold the cap pressed down on said gasket.
- 35 45

running down on the outside of the nozzle, said nozzle being formed with outwardly pressed and projecting hollow shoulders, a gasket resting on said lip of the nozzle, and a sheet metal cap bearing on said gasket and 50 having a peripheral flange depending below said shoulders, the lower part of said depending flange being bent inwardly at intervals to form flanges to engage under said shoulders of the nozzle, the said flanges being formed with upwardly bent parts in line with said shoulders to be arrested by said shoulders when the cover is turned into sealing position.

3. A sheet metal nozzle for containers 60 formed at its mouth with a marginal lip and formed with outwardly bent and projecting hollow shoulders, a gasket resting on said lip of the nozzle, and a sheet metal cap bearing on said gasket and having a 65 peripheral flange depending below said shoulders, the lower part of said depending flange being bent inwardly at intervals to form flanges to engage under said shoulders of the nozzle, the said flanges being formed 70 with upwardly bent parts to be arrested by said shoulders when the cover is turned into sealing position.

4. A sheet metal nozzle for containers 75 formed at its mouth with an inward peripheral bend to obstruct the flow of liquid which is desired to be delivered by drops, said inward bend terminating in an upwardly and outwardly turned marginal lip which, together with the concave outside 80 contour of the nozzle at said bend, prevents the fluid from running down on the outside of the nozzle and drains any residue back into the container, a gasket resting on the top of said lip of the nozzle, and a sheet 85 metal cap bearing on said gasket, said nozzle and cap having detachable interlocking means to hold the cap pressed down on said gasket.

JOHN M. HOTHERSALL.
